TOY BLACKBOARD

Howard M. Fancher, Rochester, N. Y., assignor
to The Rochester Folding Box Co., Rochester,
N. Y., a corporation of New York

Application August 16, 1933. Serial No. 685,399

6 Claims. (Cl. 35—10)

This invention relates to toy blackboards and has for its object the provision of a simple, relatively inexpensive toy blackboard suitable for use by children, of neat and attractive appearance, which can be collapsed into a compact package or erected readily into a condition suitable for use.

To these and other ends the invention resides in certain improvements and combinations of 10 parts, all as will be hereinafter more fully described, the novel features being pointed out in the claims at the end of the specification.

In the drawing:

Fig. 1 is a perspective view of a blackboard 15 constructed in accordance with a preferred embodiment of the invention, showing it erected in position for use;

Fig. 2 is a side elevation of the blackboard in the same position shown in Fig. 1;

Fig. 3 is a side view of the blackboard in collapsed position; and

Fig. 4 is a section through the chalk holding container and abutment means of the blackboard.

The same reference numerals throughout the several views indicate the same parts.

The blackboard of the present invention comprises what may be termed a base portion, to one edge of which is hingedly connected a supporting portion 2 adapted, when the blackboard is erected as in Figs. 1 and 2, to extend obliquely upwardly from its hinge connection, as shown. A writing portion 3 is hingedly connected to the supporting portion 2 and, when erected, extends obliquely downwardly as shown in Figs. 1 and 2, with the lower edge of the portion 3 resting upon the base portion 1 at a point materially spaced from the hinge connection between the portion 1 and the portion 2.

A chalk-taking surface, preferably of a black background so that white chalk will show readily thereon, is provided on one or both sides of some or all of the above mentioned portions. Such a chalk-taking surface on the front side of the writing portion 3 is indicated diagrammatically at 4. In order to make the device of educational value to children, a suitable portion of the device may have the letters of the alphabet printed thereon as indicated at 5, and numerals 45 or other signs as indicated at 6.

Adjacent the front edge of the base portion 1 is suitable chalk containing means indicated in general by the numeral 7, which means serves also as an abutment against which the lower 55 edge of the writing portion 3 may thrust when

the blackboard is in erected position, to prevent this lower edge from sliding along the base 1 and to hold the parts in erected position, as will be plainly apparent from Figs. 1 and 2 of the drawing. This chalk holding means and abutment 60 7 may be constructed in any suitable manner to serve its intended two-fold purpose, but preferably is in the form of a slide 8 within an outer covering or tube 7, as shown in Fig. 4. This tube portion 7 is open at both front and back, and 65 the child's fingers may be pressed against the front edge of the slide 8 within the tube, in order to push the slide rearwardly so that the rear edge thereof is projected outwardly from the enveloping tube, enabling a flap 9 on the slide to 70 be opened up to obtain access to sticks of chalk or the like indicated at 10.

The members 1, 2, and 3 are preferably all 75 constructed from a single strip of suitable material which is relatively rigid but which may be creased and bent at the desired points. For example, corrugated fiberboard of the type having smooth flat sheets on each side, is admirable for this purpose and is the preferred material from which the portions 1, 2, and 3 are made. 80 The abutment means and chalk container may be made of any suitable cardboard or fiberboard, suitably secured by gluing, stapling, or other means to the base portion 1.

The member 3 is made slightly shorter than 85 the member 2 so that it may be folded back against the member 2 and will not interfere with folding the members 2 and 3 together down onto the base 1, as indicated in Fig. 3. The distance from the rear edge of the base portion 1 to the 90 rear edge of the chalk holder and abutment means 7, is preferably substantially equal to the length of the supporting portion 2, so that when the latter is folded down it will substantially fill the space from the rear edge of the base portion 95 1 to the chalk container 7, as plainly indicated in Fig. 3. This makes a neat and compact package when the parts are thus folded to collapsed position. It is also advantageous to make the 100 member 7 of a height substantially equal to the combined thickness of the members 2 and 3 when they are folded to collapsed position, as indicated in Fig. 3, so that the entire article when thus folded up has a regular outline and is substantially flat on both sides.

Another advantage of this construction is that when the parts are collapsed as in Fig. 3, the edges of the members 2 and 3 lock the chalk holding means in closed position and prevent the slide 110

member 8 from being accidentally pushed rearwardly to open position.

Merely for convenience of description, the portion 2 has been referred to as a supporting portion, and the portion 3 has been referred to as a writing portion, but it will be understood that the child or other user of the device may write upon any desired portion of the structure and writing is not necessarily confined to the portion 3, although ordinarily the front side of the portion 3 is in the most convenient position for writing, when the structure is held on the child's lap, for example.

While one embodiment of the invention has been disclosed, it is to be understood that the inventive idea may be carried out in a number of ways. This application is therefore not to be limited to the precise details described, but is intended to cover all variations and modifications thereof falling within the spirit of the invention or the scope of the appended claims.

I claim:

1. A toy blackboard comprising a base portion, a supporting portion hinged to said base portion and adapted, when in erected position, to extend obliquely upwardly, a writing portion hinged to said supporting portion and adapted, when in erected position, to extend obliquely downwardly and to rest loosely upon said base portion at a point materially spaced from said supporting portion, a chalk-taking surface on at least one of said portions, and a chalk holding box having a part secured to said base portion and acting as an abutment for holding said writing portion against movement in one direction along said base portion.

2. A collapsible toy blackboard comprising a base portion, a supporting portion hingedly connected to said base portion and adapted, when in erected position, to extend obliquely upwardly from its connection with said base portion, a writing portion hingedly connected to said supporting portion and adapted, when in erected position, to extend obliquely downwardly from its connection with said supporting portion and to rest upon said base portion at a point materially spaced from the connection of said supporting portion to said base portion, a chalk-taking writing surface on at least one of said portions, and abutment means on said base portion against which said writing portion may thrust when in normal erected position, to limit movement of said writing portion in one direction along said base, said writing portion being capable of being folded against said supporting portion and said supporting portion and writing portion together being capable of being folded down substantially flat onto said base portion with the writing portion beneath and the supporting portion on top to form a compact collapsed package.

3. A construction according to claim 2 in which said base portion, supporting portion, and writ-

ing portion are all made from a single strip of relatively stiff material capable of being folded.

4. A construction according to claim 2 in which said base portion, supporting portion, and writing portion are all made from a single strip of 80 corrugated fiberboard.

5. A collapsible toy blackboard comprising a base portion, a supporting portion hinged to the base portion, a writing portion hinged to said supporting portion, said supporting and writing portions being adapted to be doubled upon themselves and folded down substantially flat against said base portion with the writing portion next to the base portion and the supporting portion above the writing portion when said blackboard is collapsed, and to be erected into an inverted V-shaped structure rising from said base portion when said blackboard is erected, a chalk-taking writing surface on at least one of said portions, and combined chalk holding means and abutment means mounted on said base portion and acting as an abutment against which said writing portion may thrust to hold said inverted V-shaped structure in erected position, said combined chalk holding means and abutment means being spaced 90 from the hinge connection of said supporting portion to said base portion through a distance substantially equal to the length of said supporting portion and being of a height substantially equal to the combined thickness of said supporting portion and writing portion, so that when said supporting portion and writing portion are folded down against said base portion, the joined ends of said supporting portion and writing portion will lie closely adjacent said means and the 95 top of said means will be substantially flush with the top surface of said supporting portion.

6. A collapsible toy blackboard comprising a base, a first portion hingedly connected at one edge to one edge of the base, a second portion 100 hingedly connected at one edge to the opposite edge of the first portion, a chalk-taking writing surface on at least one of said portions, said first and second portions being erectable into an upstanding inverted V-shaped structure with a 105 free edge of said second portion resting loosely on said base and being collapsible into a relatively flat structure with said first and second portions lying flat on said base, and combined chalk holding and abutment means mounted on said base 110 and serving to hold said free edge of said second portion against movement along said base in one direction when the portions are in erected position, said means comprising a tubular wrapper secured to said base and a slide member movable 115 within said wrapper and capable of being projected from said wrapper to obtain access to chalk within said slide member, said first and second portions, when collapsed lying flat on said base, serving to lock said slide member against 120 being projected from said wrapper.

HOWARD M. FANCHER.
